(57) **CLAIM**

The ornamental design for a dual operation crimp and press jawset, as shown and described.

DESCRIPTION

FIG. 1 is a front perspective view of an assembled jawset in accordance with a second embodiment;

FIG. 2 is a rear perspective view of the assembled jawset of FIG. 1;

FIG. 3 is a top plan view of the assembled jawset of FIGS. 1 and 2;

FIG. 4 is a bottom plan view of the opposite side of the assembled jawset of FIGS. 1 and 2 rotated one half turn;

FIG. 5 is a front elevational view of the assembled jawset of FIGS. 1 and 2;

FIG. 6 is a rear elevational view of the assembled jawset of FIGS. 1 and 2;

FIG. 7 is a side elevational view of the assembled jawset of FIGS. 1 and 2; and,

FIG. 8 is a side elevational view of the opposite side of the assembled jawset of FIGS. 1 and 2 rotated one half turn.

The dot and dash lines in FIGS. 1–8 are for illustrative purposes only showing environmental subject matter and form no part of the claimed designs.
